A. Currie

UNITED STATES PATENT OFFICE.

WILLIAM JOHN CHERRY, OF NEW YORK, N. Y.

BOOK-HANGER.

1,285,939.

Specification of Letters Patent. Patented Nov. 26, 1918.

Application filed November 19, 1917. Serial No. 202,814.

To all whom it may concern:

Be it known that I, WILLIAM JOHN CHERRY, a citizen of the United States, and resident of New York, in the county of New York and State of New York, have invented 5 certain new and useful Improvements in Book-Hangers, of which the following is a specification.

This invention relates to book hangers 10 and more particularly to a book hanger adapted for application to books, such as directories or other reference books, which are provided with a perforated corner adapted to receive a device whereby the 15 book may be suspended from a convenient hook, nail, or other member.

The invention has for an object to provide a book hanger of this type in which 20 simplicity of construction and ease of application are combined and which also will be adapted to accommodate itself to convenient suspension of the book in such different positions as local conditions may render desirable.

25 A further object is to provide a hanger capable of adhering closely to the general outline of the book to permit of close packing of the latter in quantities for shipment with the hanger applied thereto.

30 For further comprehension of the invention, and of the objects and advantages thereof, reference will be had to the following description and accompanying drawings, and to the appended claims in which 35 the various novel features of the invention are more particularly set forth.

Figure 1 of the drawings is a perspective view of the hanger showing it applied to a book.

40 Fig. 2 is a side elevation thereof with the book shown in transverse section.

Fig. 3 is an elevation of the hanger taken at right angles to Fig. 2.

Fig. 4 is a top end view of the hanger.

45 As shown in the drawings the hanger comprises a single length of preferably steel wire bent upon itself between its ends to form a loop 2 for attachment to a hook or the like, further reference to this loop being 50 presently made.

55 One end of the wire is bent back upon itself for a distance preferably slightly less than the thickness of the book, a portion of which is shown at 3, to constitute a narrow loop 4 which is inserted crotch end foremost

in the transverse perforation 5 formed in the upper rear corner of the book.

The other end of the wire is continued downwardly from the loop 2 along the face of the book, as shown at 6, and the extreme 60 end thereof is bent upwardly to form a hook 7 which is adapted to engage in the crotch 8 of the loop 4.

Between the suspension loop 2 and the narrow loop 4 the wire is bent horizontally 65 as at 10 across and slightly spaced from, the top of the book, and then downwardly along the book as at 11.

As will be apparent from the drawings 70 the crotch of the loop 4 forms, when the hanger is applied to a book, an eye located substantially flush with the face of the book and in which the hook 7 engages.

The suspension loop 2 preferably extends 75 in a general plane at an angle of 45 degrees to the general plane of the book, as indicated by the line α — α in Fig. 4. The two reaches 80 of the loop however, which extend upwardly from the portions 6 and 10 of the hanger, are bent outwardly in curves whose planes 85 are respectively co-incident with the face of the book and at right angles thereto. These two reaches preferably join one another in the form of a downwardly extending U-shaped tongue 15.

85 This arrangement in effect provides a pair of hooks 2' and 2^a, one of which extends in the general plane of the book and the other of which extends transversely thereto.

The book may be suspended from either 90 hook as desired. For instance, if suspended from a hook or the like projecting from a wall or other flat surface of extensive area, the hook 2' would naturally be employed, whereas if suspended from the small hook 95 with which wall telephones are usually provided, and which generally project parallel with the wall and only an inch or two therefrom, the transverse hook 2^a would be the most convenient.

100 In order to enable the hanger to be thrown over to lie close against the top of the book for shipping I have shown the suspension loop as extending at an angle, or inclined, to the general plane of the portions 6 and 11, 105 this being more clearly shown in Fig. 3. This angle is calculated in conjunction with the clearance between the horizontal portion 10 and the top of the book so that when the loop 2 is swung down to lie on the book, 110

as shown in dotted lines, it will contact closely therewith throughout its entire length, the hook 2^a lying on the top of the book and the hook 2' along the side of 5 the latter.

It is believed that the method of application of the hanger to a book will be apparent from the foregoing description, the resiliency of the metal permitting the hooked end 10 to be sprung to one side while the loop 4 is being inserted in the perforation 5.

If desired, the tongue 15 may be omitted, as indicated by the dotted line 20 in Fig. 3, 15 the general arrangement of the loop 2 permitting the hanger to be readily suspended from differently located hooks as above pointed out.

What I claim is:—

1. A book hanger for perforated books 20 comprising a single length of wire provided with means adapted to engage in the perforation in the book, said hanger having a suspension loop whose general plane is at an angle of 45 degrees to the face of the book.

2. A book hanger for perforated books comprising a single length of wire provided with means adapted to engage in the perforation on the book, said hanger having a 30 suspension loop whose general plane is at an angle of 45 degrees to the face of the book and whose opposite reaches are bent in curves extending respectively parallel and transversely to the face of the book.

3. A book hanger for perforated books 35

comprising a single length of wire provided with means adapted to engage in the perforation on the book, said hanger having a suspension loop bent to form a pair of hooks extending respectively parallel and transversely to the face of the book. 40

4. A book hanger for perforated books comprising two main loops one of which engages in the perforation in the book and has one side thereof extending across the top 45 edge of the book, the other being a suspension loop, the latter loop being inclined with respect to the former, for the purpose set forth.

5. A book hanger having book engaging 50 means and provided with a suspension loop bent to form a pair of hooks extending respectively parallel and transversely to the face of the book.

6. A book hanger for perforated books 55 comprising a substantially rigid member having a book engaging portion and a suspension loop, said suspension loop being substantially narrower at its upper end than the thickness of the book, said member being bent to cause said loop to contact throughout its length with the top of the book when 60 swung down thereagainst.

Signed at New York, in the county of New York and State of New York, this 65 16th day of November, A. D. 1917.

WILLIAM JOHN CHERRY.
